UNITED STATES PATENT OFFICE.

AUGUSTUS WOOD, OF FITCHBURG, MASSACHUSETTS, ASSIGNOR TO MANNING, MAXWELL & MOORE, INC., OF NEW YORK, N. Y., A CORPORATION OF NEW JERSEY.

DRIVING DOG FOR LATHES.

Application filed February 1, 1921. Serial No. 441,702.

To all whom it may concern:

Be it known that I, AUGUSTUS Wood, a citizen of the United States, and resident of Fitchburg, in the county of Worcester and 5 State of Massachusetts, have invented new and useful Improvements in Driving Dogs for Lathes, of which the following is a specification.

This invention relates to driving dogs for 10 lathes and has for its object the provision of an automatic-bite driving dog characterized by simple and substantial construction, ease and accuracy of adjustment, and regulated or restrained depth of bite into the 15 work. In particular, the improved driving-dog herein described is adapted to that class of lathes commonly known as wheel lathes which are used for turning the tires of railway rolling-stock wheels, mounted on 20 their axles.

Driving dogs, such as herein described, are affixed to the face plate of a wheel lathe, and impart movement to the work mounted in the lathe by means of a toothed 25 bit which forms part of the driving dog, and is adapted to set its teeth with firm engagement into the wheel of which the tire is being turned.

In the drawings hereto annexed, which 30 show the structure of a driving dog embodying and illustrating my invention and improvement,

The invention accordingly consists in the features of construction, combinations of 35 elements and arrangement of parts which will be exemplified in the construction hereinafter set forth, and the scope of the application of which will be indicated in the following claims.

40 Figure 1 is a view of a driving-dog, in side elevation, partly broken away to show sections of the bracket, bit, and other parts;

Figure 2 is an end elevation, viewed from the left of Figure 1,

45 Figure 3 is a top plan view, and

Figure 4 is an end elevation viewed from the right of Figure 1.

In the drawings there is illustrated a work 50 engaging bit and means for mounting it upon a face plate or the like for movement in a direction inclined toward the work; as illustrated. The bracket 1 is provided with a base 1^b adapted to attachment to the face-plate of a lathe, as by bolts 2, in the usual 55 manner. In the outer part of the bracket

there is formed the way 1^a inclined to the base at an angle suited to produce the automatic bite of a work engaging bit 4 into the work. An angle of inclination of 20 degrees has been found effective for this 60 purpose. A hardened plate 3 is fixed in the way 1^a, and the bit 4 is arranged in the way, to slide on this bearing-plate 3. The bit 4 has the usual teeth or serrations 4^a to engage and drive the work in unison with the 65 rotating face plate of the lathe; and in its base-portion is bored from end to end, the portion 4^b being smooth and slightly larger in diameter than the portion 4^c, which is internally threaded to engage a threaded 70 bolt 5.

The threaded bolt 5 is slidably mounted in the bracket; more precisely its unthreaded portion 5^b passes slidably through an abutment-block 6, which is fixed to the 75 bracket 1 by means of pins 7, 7. The outer part of the bolt 5 is screw threaded at 5^c; nuts 8, 8 engage the thread at 5^c, and these nuts constitute or represent the stop which regulates and controls the sliding movement, and consequently the depth of bite, of 80 the bit 4 into the work. At its outermost end, the bolt 5 is shaped at 5^d to receive a turning wrench.

Between the bit-engaging thread and the 85 part 5^b, the bolt 5 is provided with means such as the shoulder 5^a for seating against the bracket; in the specific arrangement here shown, for seating against the block 6, which is practically a part of the bracket. 90 At the end which lies at the other side of its thread-engagement with the bit 4, the bolt 5 is shaped as at 5^e to afford a seat for the spring 9, which is held on the plate 11, this plate being secured by bolts 12, 12 to 95 the bracket 1. In order to exclude foreign matter such as metal chips and grit from the threaded seat of the bolt 5 in the bit 4, a felt or fiber washer 10 is provided.

The operation of the above described driving dog is as follows: The bracket 1 being bolted to the face plate of the lathe, and the bit 4 being clear of the work, the stop nuts 8, 8 are backed away from the abutment block 6 if necessary, and by means of 105 a wrench applied to the end 5^d of the bolt 5, the bit 4 is advanced along the inclined way 1^a toward the work until its teeth 4^a come in contact with the wheel rim, or other work which has been placed in the lathe. The 110

pressure produced by this contact is sustained by the seat of the bolt 5, at 5^a, against the abutment block 6 of the bracket 1. This setting of the bit 4 does not compress the spring 9, which bears on the end of the bolt 5.

The proper limit of further bite of the bit 4 against and into the work having been determined either by precalculation or experience, the stop nuts 8, 8, are now turned forward and set at such a distance from the abutment block 6 that, when the power of the lathe is applied to the work and the bit 4 responds by sliding up the inclined way 1^a on the bearing plate 3, the stop nuts 8 will abut against the abutment block 6 and thus impose a limit to the end thrust exerted on the work by the wedging-action of the bit 4 and its inclined bearing on the bracket. The permitted sliding movement of the bit 4, after it has made first contact with the work, will be slight, so that the spring 9 which is compressed when the bit 4 and bolt 5 move together up the inclined way 1^a, undergoes but little increment of distortion. As this spring is normally under compression, as soon as the lathe stops, the spring moves the bit 4 and bolt 5 down the inclined way 1^a away from the work until the shoulder 5^a seats against the abutment plate 6 of the bracket 1.

In the actual operation of the lathe, the bolt 5 and nuts 8, 8, constitute and perform the function of a stop directly and rigidly attached to the bit 4, the block 6 furnishing the coacting abutment for the stop. In the preparatory operations, the screw thread engagement of the bolt 5, which attaches the stop to the bit, enables the length of the stop attachment to be adapted to the particular work in hand; and the adjustability of the stop (as by such means as the nuts 8, 8) enables the relation of the stop to its abutment to be the same, no matter at what part of the inclined way the bit may be when it is set against the work.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What I claim, and desire to secure by Letters Patent is:

1. In a device of the character described in combination, a work engaging bit, means for mounting said bit upon a face plate or the like for movement in a direction inclined toward the work, a stop for limiting the movement of said bit toward the work, and means for adjusting said stop.

2. In a device of the character described

in combination, a work engaging bit, means for mounting said bit upon a face plate or the like for movement in a direction inclined toward the work, means for adjustably limiting the movement away from said work, and means for adjustably limiting the movement toward said work.

3. In a device of the character described in combination, a work engaging bit, means for mounting said bit upon a face plate or the like for movement in a direction inclined toward the work, means for adjustably limiting the movement away from said work, and means for adjustably limiting the movement toward said work, and resilient means for urging said bit against said first mentioned limit.

4. In a device of the character described in combination, a bit supporting member, means for mounting said member upon a face plate or the like, for movement in a direction inclined toward the work, means for limiting the movement of said member away from said work and a work engaging bit adjustably mounted on said member.

5. In a device of the character described in combination, a bit supporting member, means for mounting said member upon a face plate or the like, for movement in a direction inclined toward the work, means for limiting the movement of said member away from said work, means for adjustably limiting the movement toward said work, and a work engaging bit adjustably mounted on said member.

6. In a device of the character described in combination, a work engaging bit, means for mounting said bit upon a face plate or the like for movement in a direction inclined toward the work, a stop for limiting the movement of said bit toward the work while in engagement with said work.

7. In a driving-dog for a lathe, the combination of a bracket having a base attachable to the face plate of a lathe and a way inclined to the base, a work-engaging bit slideable in said way, an adjustable stop attached to said bit, and an abutment to engage said stop.

8. In a driving-dog for a lathe, the combination of a bracket having a base attachable to the face plate of a lathe and a way inclined to the base, a work-engaging bit slideable in said way, a bolt in screw-threaded engagement with the bit, slidably mounted on and seating against said bracket, a stop mounted on said bolt, and an abutment to engage said stop.

9. In a driving-dog for a lathe, the combination of a bracket having a base attachable to the face plate of a lathe and a way inclined to the base, a work-engaging bit slideable in said way, a bolt in screw-threaded engagement with the bit, slidably mounted on and seating against said bracket, an ad-

justable stop mounted on said bolt, and an abutment to engage said stop.

10. In a driving-dog for a lathe, the combination of a bracket having a base attachable to the face plate of a lathe and a way inclined to the base, a work-engaging bit 5 slidable in said way, a bolt in screw-threaded engagement with the bit, slidably mounted on and seating against said bracket, a stop 10 mounted on said bolt, and an abutment to engage said stop, and a spring engaging the end of said bolt normally urging the bolt to its seat against the bracket.

11. In a driving-dog for a lathe, the com-

binatiion of a bracket having a base attachable to the face plate of a lathe and a way inclined to the base, a work-engaging bit 15 slidable in said way, a bolt in screw-threaded engagement with the bit, slidably mounted on and seating against said bracket, an adjustable stop mounted on said bolt, and an abutment to engage said stop, and a spring 20 engaging the end of said bolt normally urging the bolt to its seat against the bracket.

Signed by me at Fitchburg, Massachusetts, 25 this twenty second day of January, 1921.

AUGUSTUS WOOD.
